(57) **CLAIM**

The ornamental design for a vial with a hook, as shown and described.

DESCRIPTION

FIG. 1 is a perspective view of a vial in an environment showing my new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top elevational view thereof; and,

FIG. 7 is a bottom elevational view thereof.

It should be appreciated that the broken lines are merely illustrative of the environment of the design, and not part of the claimed design.
